UNITED STATES PATENT OFFICE.

JAMES A. JONES, OF LOGANSPORT, INDIANA.

MACHINE FOR CLEANING BLACKBOARD-ERASERS.

SPECIFICATION forming part of Letters Patent No. 699,957, dated May 13, 1902.

Application filed January 14, 1902. Serial No. 89,755. (No model.)

To all whom it may concern:

Be it known that I, JAMES A. JONES, a citizen of the United States, residing at Logansport, in the county of Cass and State of Indiana, have invented certain new and useful Improvements in Machines for Cleaning Blackboard-Erasers; and I do hereby declare the following to be a full, clear, and exact description of the invention, such as will enable others skilled in the art to which it pertains to make and use the same.

My invention relates to machines for cleaning erasers, has especial reference to erasers used for cleaning school and other blackboards, and consists in certain improvements in construction, which will be fully disclosed in the following specification and claims.

In the accompanying drawings, which form part of this specification, Figure 1 is a perspective of my improved machine; Fig. 2, a top plan view with the cover of the casing thrown back; Fig. 3, an end elevation with the end of the casing removed; Fig. 4, a vertical transverse section on line 4-4, Fig. 2; Fig. 5, a perspective of one of the eraser-holders, the table on which the erasers are beaten, and the eraser-feed mechanism; Fig. 5^a, a transverse section of an eraser-holder; Fig. 6, an elevation showing the eraser-feeding mechanism; Fig. 7, a perspective of one of the tables on which the erasers are beaten; Fig. 8, a side elevation of the mechanism for operating the eraser-beaters, and Fig. 9 a perspective of the brackets which support the cam-shaft.

Reference being had to the drawings and the numerals thereon, 1 indicates an inclosing case or box in which the machinery is supported and whose cover 2 is hinged thereto and provided with ingress-passages 3 for the introduction of erasers 4, and on the inside of said cover and directly under the openings or passages 3 are doors 5, normally held to their seats on the cover 2 by springs 6, one end of which engages an arm 7 on a rod 8, to which the doors are secured to move therewith, and the opposite ends of the springs are secured to the cover, as shown in Figs. 2 and 4. The doors are opened by the person operating the machine by pushing an

eraser through the passage 3, as shown in Fig. 4.

The machine illustrated shows three sets of cleaning mechanisms, each being a duplicate of the other and all driven from one source 55 of power, and each is provided with a chute 9, supported by brackets 14 for conducting erasers located below the opening 3, and its door or closure 5 is cut away at 10 to allow the door to open and at 11 to allow the eraser 60 to clear the chute as it falls upon the feed-roll below the chute. (See Fig. 4.)

12 is a table or plate extending across the machine and secured to the case 1 by bolts 13 or in any other preferred manner, is provided with perforations 14' to lighten the casting, with an opening 15, in which feed-rolls 16 17 operate to engage the face of erasers to feed them to the eraser-holder 18, a perforated section 19, on which erasers are beaten, and an opening 20, passing through which the erasers are engaged by a brush 21 to remove any loose dust on the face of the eraser after it has been beaten. The erasers are engaged on one side by a feed-roll 22 and 65 on the opposite side by a resilient arm or spring 23 to guide the erasers to the holder 18 and the roll 22 to assist the rolls 16 and 17 in feeding the erasers to the eraser-holder. The arm 23 is supported in a post 24 on the 70 table 12 and is set to engage and hold the erasers in line with the eraser-holder while the roll 22 is pressing against the opposite side of the erasers. The rolls 16 are supported on a shaft 25, the rolls 17 on shaft 75 26, to which motion is imparted by sprocket-wheels 27 28, chain 29 engaging sprocket-wheel 30 on the power-shaft 31, to which motion is imparted by crank 32, and on the shaft 26 are miter gear-wheels 33, which engage 80 like wheels 34 on shafts 35, which support rolls 22. (See Fig. 6.) The brushes 21 are supported on shaft 36, provided with pulley 37, engaged by belt 38, which belt engages pulley 39 on shaft 40, driven by the fly-wheel 90 41 engaging pulley 42 on shaft 40. The fly-wheel and the pulley 42 are covered with a suitable friction-surface 43 on the former and 44 on the latter.

45 represents vertically-movable members 100

or rods to which the eraser-holders are attached and connected to arms 46 on the shaft 47 by links 48 to raise the erasers 4 and beat them on the perforated section 19 of the tables 12, the rods 45 being returned and the erasers beaten by the resiliency of a spring 49 engaging one of the crank-arms 46 and secured at its ends to the tables 12 by bolts 50 50, as shown in Fig. 2, and the rods are 10 guided in brackets 51, secured to one side of the case 1, the shaft 47 being supported on brackets 52, resting on the tables 12.

Each eraser-holder 18 is provided with a spring 53, secured thereto to extend down 15 over its sides, as shown in Figs. 3, 5, and 5^a, to engage and secure an eraser to the holder while it is being beaten, and the erasers are automatically released after they have been beaten by rods 54, having right-angled ends 20 55, which engage the spring, and the opposite ends of said rods 54 are provided with cranks 56, connected by a wire 57, and the wire is connected to an elongated link-like trip 58, whose lower end enters a groove 59 25 in the feed-roll 17 while erasers are being beaten and strikes against the upper surface of an oncoming eraser toward the holder 18 and turns the rods 54 on their axes, which press the springs 53 out from the holder and 30 release the erasers. The lower face 60 of the holder 18 is convex to fit the concave upper surface 61 of an eraser, and the trip-link 58 is guided in loops 62 on the eraser-holder.

From the shaft 47 extends an arm 63, (see 35 Figs. 2, 4, and 8,) provided with a friction-roller 64, which is engaged by arms 65 on shaft 66 for raising the rods 45 and the erasers. The shaft is supported in adjustable bearings 67 on brackets 68 and is driven by a chain 40 69 engaging a sprocket-wheel 70 on said shaft and a sprocket-wheel 71 on shaft 72, which shaft is provided with sprocket-wheel 89, and said sprocket-wheel is connected to sprocket-wheel 30 on the main power-shaft 45 by a chain 73. (See Figs. 2 and 3.)

The feed-rolls 16, 17, and 22 are covered 50 with a friction-producing substance, such as felt or its equivalent, as shown at 74 in Figs. 4 and 5, and the erasers as they leave the tables 12 are brushed and fall upon doors 75 and are discharged from the machine, and the doors are again closed automatically by springs 76 engaging an arm 77 on the rod 78 at one end and secured to the case at the opposite end.

The erasers are guided on the plate 12 by 55 vertical flanges 79 to keep them in line with the eraser-holder and the brush 21, and the dust removed from the erasers is collected in a tray or drawer 80 and removed from the inclosing casing through opening 81.

Having thus fully described my invention, what I claim is—

1. An eraser-cleaner having a movable 65 member, an eraser-holder secured to said

member, and means for automatically engaging and disengaging an eraser.

2. An eraser-cleaner having a movable member, an eraser-holder secured to said member, springs for securing an eraser thereto, and an automatically engaging and disengaging mechanism. 7c

3. An eraser-cleaner having a movable member, an eraser-holder secured to said member and provided with a convex face, 75 springs on the sides thereof, and a tripping device connected to said springs.

4. An eraser-cleaner having a movable member provided with a block having eraser-engaging springs thereon, a vertically-movable tripping-rod, and connections between the springs and said rod. 80

5. An eraser-cleaner having a movable member, an eraser-holder secured to said member, and means for feeding erasers to the 85 eraser-holder.

6. An eraser-cleaner having a movable member, an eraser-holder secured to said member and a revolute feed device engaging the side of an eraser to feed the eraser 90 to the holder.

7. An eraser-cleaner having a movable member, an eraser-holder secured to said member, and rolls engaging one side and one face of an eraser. 95

8. An eraser-cleaner having a movable member, an eraser-holder secured to said member, a perforated plate on which erasers are beaten, and means for feeding erasers to the holder. 100

9. An eraser-cleaner having a movable member, an eraser-holder secured to said member, and a brush for engaging the face of an eraser after it has been beaten.

10. An eraser-cleaner having a movable 105 member, an eraser-holder secured to said member, an eraser-feed mechanism, a perforated plate on which the erasers are beaten, an opening in said plate beyond the perforations, and a brush engaging the face of an eraser 110 while passing over said opening.

11. An eraser-cleaner having a movable member, an eraser-holder secured to said member and provided with springs to engage an eraser, levers engaging the springs, rolls 115 for feeding erasers to the eraser-holder, one of which rolls is provided with a groove, and an elongated link-like trip engaging the grooved roll.

12. An eraser-cleaner having a movable 120 member provided with an eraser-holder having springs to engage an eraser, a roll and a resilient rod engaging the sides of an eraser, rolls engaging the face of the eraser, and an automatic tripping device for releasing an 125 eraser from the holder.

13. An eraser-cleaner having an inclosing casing, inlet and discharge eraser-openings provided with closures, means for beating erasers, a chute for conducting erasers, and 130

means for feeding erasers to the holders of the beating mechanism.

14. An eraser-cleaner having a plurality of movable members provided with eraser-holders, means for feeding erasers to each holder, a shaft having cranks connected to said movable members, and an operating mechanism engaging said shaft.

15. An eraser-cleaner having a movable member provided with an eraser-holder, a table or plate on which erasers are beaten hav-

ing an opening therein, feed-rolls under the plate and in said opening, a chute above the opening, a discharge for erasers, and means for imparting motion to the movable member. 15

In testimony whereof I affix my signature in presence of two witnesses.
